Application June 27, 1934, Serial No. 732,593

9 Claims. (Cl. 78—83)

In the production of the strip metal or skelp from which welded tubes are made, a piece of metal, which may be a billet or a bloom, or even an ingot, is heated in a furnace to the temperature for rolling, and is then withdrawn from the furnace and put through a number of rolling passes each of which effects a reduction in the thickness of the material, so that it emerges from the last pass with the correct gauge for the size of tube to be manufactured. For convenience, the term "billet" will be used in this specification in a general sense, as meaning any relatively short and massive starting piece from which skelp may be rolled at a single furnace heat.

Since the material is elongated as its thickness is reduced, the speed of travel of the metal increases with each successive rolling pass, and the skelp comes from the final pass at high speed. The skelp may be cut to desired lengths by a flying shear located at the end of the skelp mill, or the skelp may be wound into rolls. In either case the metal must later be re-handled and reheated to produce a welded pipe or tube.

In some plants, skelp from the last rolling pass goes directly into a forming mill, which bends the hot skelp into an open-seam tube, the result being that the billet is changed into a completely formed open-seam tube in a continuous or substantially continuous operation.

By an "open-seam tube" in this specification is meant a fully formed but unwelded tube in which the opposing seam edges are adjacent one another, or in contact.

It has long been recognized that great economies in space, heat, time, and handling and large increase in production could be effected if the heated billet could be rolled, tubularly formed, and welded in a continuous operation. Various plans have been proposed, but so far as I am aware no satisfactory method has been devised for producing welded pipe or tube in such a manner.

In modern rolling mills the skelp comes from the skelp mill at speeds of 600—1000 feet, or more, per minute. An open-seam tube can be formed at this speed, or at higher speeds, but even though the tube issues from the forming mill with much of the original heat left in it, the addition, at this high speed, of heat necessary to raise the edges to a welding state has been a difficult if not unsolved problem. The plans which have been proposed for heating fast-moving tube edges include electrical resistance heating; heating by a seamwise-extended system of gas flames, or electric arcs; and heating by friction discs extending

into the seam in contact with opposing edges and rotated at high speed. Such plans contemplated the production of pressure welds, and were proposed many years ago when final rolling speeds were of the order of 300—400 feet per minute. As 5 stated, final rolling speeds are now of a different order, the development being in the direction of high speeds. With this invention hot-rolled skelp can be welded at these high speeds.

An apparently insurmountable difficulty to the 10 making of welds at final rolling speed has been the time element, and for fusion welds the rate of heat transfer by conduction through the metal of the tube edges.

It is an object of this invention to provide a 15 method and apparatus by which high-quality welded pipe or tube is made from a heated billet in continuous operation. Pipe and tube can be made under this invention with no oxide in the weld and of better qualities in the weld than in 20 the body of the tube.

One of the objects of this invention is therefore, to provide a method and apparatus by which welded pipe or tube of uniformly good quality can be made from a heated billet in continuous 25 operation. While the use of the invention is not limited to the production of fusion welds only, it is an advantage of the process and apparatus herein disclosed that fusion welded pipe or tube can be made at exceedingly high speeds, such as 30 the speeds at which skelp may issue from a final skelp rolling pass. It has never before been found possible to effect progressive, longitudinal fusion welding of pipe in continuous operation with the 35 rolling of the skelp. Indeed, to the best of my knowledge, the industry has not found it satisfactory to make welded tube of any kind from the billet.

Other aspects of the invention, involving 40 combined forming or bending of the skelp to the tubular form, and welding of the edges at much higher speeds than would otherwise be possible, are applicable to the manufacture of pipe or tube from skelp already manufactured by previous, 45 separate operation.

In the preferred mode of application of the 50 invention the metal is put through rolling mill passes until it is reduced to the gauge of skelp and the skelp strip is fed through a forming mill. The skelp is heated by high temperature flames, 55 preferably those of an oxy-acetylene mixture, the flames being projected directly against the edge faces to be welded. The flames are applied to the edge faces between passes of the forming mill and ahead of the first forming pass, and 55

even to the flat skelp, the heating being so proportioned with respect to the speed of travel of the skelp that the edge faces are heated to a welding condition by the time they come together in the final forming pass.

By the use of an oxyacetylene flame mixture the skelp edges can be heated to welding state or to fusion at high rates of travel of the skelp. Other fuel gases or vapors may, however, be employed. The oxygen supplied to the flame mixture is preferably commercially pure oxygen though mixtures of fuel gas and oxygen-enriched air or the like may be used. With several stages of heating, it is possible to employ mixtures of 10 different compositions in different stages, and with a sufficiently extended edge heating system a mixture of air and fuel gas may be utilized in one or more stages.

Other features and modes of application of 20 the invention will become apparent from a consideration of the following description and of the accompanying drawings, wherein:

Fig. 1 is a diagrammatic plan view illustrating the relation of apparatus and the steps of the 25 process of this invention.

Fig. 2 is a top plan view, on an enlarged scale, of a portion of the apparatus shown in Fig. 1.

Fig. 3 is a side elevation of the apparatus of 30 Fig. 1, but showing only the last stand of the skelp mill.

Figs. 4-6 are sectional views through the skelp showing its shape at various stages during the forming step.

Figs. 7 and 8 are enlarged sectional views of 35 the heating retorts through which the skelp passes when flat and partially formed, the sections being taken on the lines 7-7 and 8-8 of Fig. 2.

Figs. 9 is an enlarged sectional view on the line 40 9-9 of Fig. 2.

Figs. 10 and 11 are enlarged detail views, partly in section, showing the rollers and mandrel illustrated in Fig. 9.

Fig. 12 is a reduced longitudinal sectional view 45 of one of the torches shown in Fig. 1.

Figs. 13 and 14 are enlarged sectional views on the lines 13-13 and 14-14, respectively, of Fig. 2.

In a continuous rolling, forming, and welding 50 operation, such as illustrated in Fig. 1, a heated billet 10 is drawn from a furnace 11 and put through the passes of a reducing mill 12, which reduces the billet to an intermediate strip. From the last pass of the reducing mill 12 this 55 strip is transferred into a first stand 14 of a skelp mill 15. The flexible metal strip is indicated by the reference character 17, the skelp and partially-formed tube by 17', and the welded tube by 17''. The metal strip 17 is threaded back and 60 forth through the successive stands of the skelp mill 15, the thickness of the strip being reduced in each stand. This mill arrangement is illustrative. All stands of a skelp mill may be in line, or in line also with preliminary reducing stands 65 in a straight-through operation.

Besides the first stand 14, the skelp mill shown in Figs. 1 and 2 has an intermediate stand 19 and a last stand 20, besides which there may be other stands or passes.

70 Passage of the metal strip 17 through the last stand 20 of the skelp mill effects the final reduction in thickness necessary to produce a skelp of the desired gauge for the tube. The reduction in the thickness of the metal in each rolling pass 75 increases the length of the strip and therefore the

lineal speed. The skelp 17 issues rapidly from the final rolling pass through the last stand 20

The skelp mill 15 is driven by a motor 22. A forming mill comprising stands 24 and 25 in line with the last stand 20 of the skelp mill receives the skelp from the final rolling pass.

The rollers of the forming stands 24 and 25 are driven from the motor 22 through gearing 26.

Before entering the final rolling pass 20, the rapidly moving hot strip 17 passes through a retort 28 in which the edges of the strip are heated, preferably by oxyacetylene flames, though other flame heating means may be employed. A guide 29 at the entrance end of the retort 28 guides the end of the strip 17 into the retort 28 and rolling stand 20 when the strip is first threaded through the skelp mill. There are similar guides at the entrances to the other rolling stands 14 and 19.

The flames in the retort 28 increase the heat of the skelp along its edges, in addition to which the hot products of combustion that sweep across the upper and lower surfaces of the strip sustain the temperature at the edges by reducing the temperature gradient from the edges to the interior of the strip. A useful effect of heating the strip in this manner before it goes through the final flat rolling pass is to eliminate a part of the mill scale then present on the strip and keep it from being rolled into the skelp surfaces.

Between the final rolling pass 20 and the first forming pass 24, the skelp travels through a retort 30, which is similar to the retort 28, and further increases the temperature of the skelp edges.

As the skelp bends from its flat condition in the retort 30 to the partially formed condition assumed in the first pass 24 of the forming mill, it travels through a retort 31 which has guides and burners shaped to conform to the change in the cross-section of the skelp as it bends under the influence of the first forming pass 24 or breakdown pass. It is not necessary to the invention that the forming be done in rolls. A forming die can be used in one or more stands, but rolls are required for feeding the metal through such a die when used in a continuous operation.

In the forming pass 24 the skelp is confined between a grooved roller 32 (Fig. 2) and a roller 33 which has a convex face extending into the groove. A section through the partially formed skelp, as it leaves the forming pass 24, is shown in Fig. 5. The center portion of the skelp is bent into an arc of 180 degrees and the side portions extend upward substantially parallel to one another. The forming in this first pass 24 may be less than that shown in the drawings, that is, the arc into which the skelp is bent may be less than 180 degrees and may extend across more or less of the width of the skelp. The amount of forming which should be imparted to the skelp in the first forming pass is largely dependent on the number of subsequent passes in the forming mill. There may be several forming passes, between certain of which the skelp may be bent to a greater degree than is shown in the drawings. Thus, the side portions of the skelp may slope inward instead of being parallel, but it is a feature of the invention that the edges of the partially formed skelp be widely spaced and so disposed that the heating flames can be applied directly against the edge faces.

This partially formed skelp section proceeds through a retort 35, which is shaped to receive the skelp in the form with which it leaves this

forming pass 24. The forward and rearward ends of the retort 35 are shaped to extend partially between the rolls of the forming mill in order to obtain the greatest possible length for the retort 5 35 within the distance between the stands of the forming mill.

The edge faces of the skelp are finally purified and are heated to surface fusion in the retort 35 and while in this state are brought together in 10 the final forming pass 25 to cause the clean fused metal on the edge faces to unite and form a strong and perfect weld. Welded tubes made in this manner can be bent sharply or flanged without breaking the weld, and can be drawn to 15 reduce the diameter and/or wall thickness. This latter operation results in a severe working of the metal and is employed to produce tubes of great strength.

If especially high-grade pipe or tubing should 20 not be required, the invention may be employed to produce pressure welded pipe or tubing of uniformly good quality and with great economy of heat. The economy of heat is made possible by the direct manner in which the heat is applied to 25 the edges and by the uniform heating which makes it unnecessary to raise the temperature of some parts of the skelp higher than necessary while bringing adjacent portions to a welding state. When the edge faces are not brought to 30 surface fusion, it is necessary to adjust the rolls in the final forming pass 20 so that the edges of the skelp are brought together under considerable pressure, or to employ a closing die or bell for obtaining such pressure.

35 All of the added heat for raising the skelp edges to surface fusion or to a welding state may be put into the edges in the retort 35 if the distance is made long enough, but in a plant such as illustrated retorts between three or more mill passes 40 are more effective and permit of very high speeds. The torches and retorts applying heat to the skelp in stages as it travels between successive mill passes makes it possible to bring the edge faces to 45 surface fusion, notwithstanding speeds of travel of the skelp as high as a thousand feet per minute, or higher.

50 Fig. 7 is an enlarged sectional view through the retort 30 with the center portion of the skelp broken out. The retort 28 is of similar construction.

55 Burner blocks 38 are located in position to direct flames, preferably oxyacetylene flames, against the edge faces of the skelp 17'. Oxygen and fuel gas are supplied to each of the burner blocks through pipes 39 and 40 connecting with a stock 41 of the burner block. The gas passages in the stocks and burner blocks need not be illustrated. It will be understood that the oxygen and fuel gas are brought together by suitable mixers 60 in the stocks 41, or in stems 42 by which the stocks are connected to the burner block, and the mixed gases distributed by longitudinal passages in the blocks, from which they issue through jet orifices. The flame system directed against 65 the edge faces of the skelp may be a single or double row of closely spaced jets, or staggered jets, or one or more ribbon flames.

70 The retort 30 comprises retort bodies 44 and 45 secured to a supporting base 46 on opposite sides of the skelp. The supporting base extends from the final stand of the rolling mill, as shown in Fig. 3. The retort bodies 44 and 45 are held in position on the base 46 by screws 47 which extend through slots 48 (Fig. 2) in the retort bodies. 75 These slots permit the retort bodies to be moved

closer or further apart to accommodate skelps of different width.

Referring again to Fig. 7, each retort body comprises upper and lower sections 49 and 50 hollowed to form a chamber 51 for the burner block 5 38, and formed with mating portions 52 and 53 at the front and rear ends. Shims 54 between these mating portions establish the proper vertical distance between the surfaces 55 and 56 of the retort sections which overlap the upper and 10 under surfaces of the margin of the skelp. The height of the skelp passages through the retort is slightly greater than the thickness of the skelp so that it can pass through these passages with 15 little friction, but the surfaces 55 and 56 serve as guides to keep the skelp substantially flat until it reaches the end of the retort and begins to bend under the pull from the rollers 32 and 33 of the first forming pass.

The shims 54 serve as side guides when the 20 front end of the skelp passes into the retort, but after the skelp has entered the rollers 32 and 33 of the first forming pass ordinarily no side guides are necessary, because these rollers have a speed 25 along their median lines slightly greater than the peripheral speed of the rolls in the final rolling pass so that the skelp is under some tension and is held in a central position as it passes through the retort 30.

Water or other cooling fluid circulates through 30 passages 58 to prevent the retort from becoming overheated. The cooling fluid enters and leaves the passages 58 through hose or pipe connections (not shown).

The retort, and likewise the other retorts, are 35 preferably made of bronze, or abrasion-resisting iron or steel, or the surfaces which contact with the skelp may be copper-plated so that they will not tend to stick to the skelp and wear excessively.

The burner blocks 38 are clamped against bosses 40 60 on the lower sections 50 of the retort by screws 61 extending through slots in the burner blocks. The heads of the screws 61 are high enough to extend through openings in the upper sections 49 so that a wrench can be conveniently applied to 45 these screws to release them when the positions of the burner blocks in the retorts are to be changed. When using oxyacetylene flames, the jet faces of the burner blocks are positioned close 50 enough to the skelp so that primary combustion 55 takes place immediately adjacent the edge faces of the skelp. The products of the primary combustion, containing reducing gases, blanket the edges, and the final products, at a temperature twice or more the skelp temperature, sweep inward 60 over the upper and under surfaces of the skelp, heating them so that heat loss from the edges by conduction into the body of the skelp is minimized. By the action of the heat and of the gases, in this and in the other retorts, the edges are deoxidized and purified and any gas pockets in the edge metal are substantially eliminated, and the highly heated skelp is protected from oxidation 65 by contact with the air.

The surfaces 55 and 56 confine the products of 70 combustion and cause them to flow across the upper and lower faces of the skelp. These surfaces may be grooved to provide more space for the flow of gases from the retort. Air for burning the products of the primary combustion enters 75 the chambers 51 around the sides and ends of the burner blocks 38. The retort bodies can be made with no space for the entrance of air around the torch blocks, in which case the oxygen for the secondary combustion may be supplied through 75

auxiliary jets opening into the chambers 51. Much of the oxygen necessary to support the secondary combustion may be supplied in the mixture fed through the flame jet openings of the torch blocks. When the hot skelp is passing through the retort, combustion becomes substantially complete within the restricted retort chambers, little or no visible flame issuing therefrom into the atmosphere.

10 Fig. 8 is a sectional view of the retort 35. This retort comprises side blocks 63, 64, which are secured to brackets 65 (Fig. 3) extending from the forming mill stands 24 and 25. The side blocks are shaped at their ends to extend part way between the upper and lower roll of each stand.

15 Referring again to Fig. 8, a center block 67 is located between the side blocks 63, 64, and held spaced from the side blocks by transverse supports 68 which are fastened to the center block 67 and side blocks 63, 64 by screws 69. With the blocks in the assembled relation shown in Fig. 8 they enclose a skelp chamber 70 and torch chambers 71 opening into the skelp chamber.

20 The skelp chamber 70 has a cross-section similar to that of the skelp 11 as it comes from the forming pass 24, but is large enough to allow sufficient space for the flow of the products of combustion downward away from the torch chambers and across the surfaces of the partially formed skelp. The most intense heat is applied directly to the skelp edges, and the products of combustion, hotter than the skelp and flowing over its surfaces, heat the body of the skelp. The high temperature gases acting on the edges reduce and purify the edge metal, so that when the edges are brought together and united, the weld that is made is free of oxide, of exceptional strength and without defects. Furthermore, the reducing action extends over the outer and inner surfaces of the skelp. By bathing the skelp surfaces, generally, as it passes through this retort, and also as it passes through preceding retorts, with hot gases more or less reducing in their action, not only is the skelp as a whole protected 25 from oxidation during these stages, but also mill scale or oxide which formed on the skelp in its progress through the rolling mill passes is virtually eliminated. The remainder of such scale is in the form of a loose powder. The elimination of mill scale by the flame gases is aided by the loosening of the scale by the bending of the skelp in the forming operation.

25 The products of combustion which pass across the outside surface of the skelp escape from the retort through slots 72 in the side blocks and through the space between the side blocks at the bottom of the retort. A conduit 73 in the center block 67 communicates with the skelp chamber 70 through slots 75. The products of combustion flowing across the inside surface of the skelp escape through the slots 75 and conduit 73. A suction pipe 76 (Fig. 9) draws the gases out of the conduit 73.

30 Referring again to Fig. 8, torches 78 and 79 are clamped against bosses on the center block 67, by screws 80 which extend through slots in the side blocks for convenient access when the torches are to be adjusted in the torch chambers to regulate the spacing of the flame jets with respect to the edge faces of the skelp. This movement of the torches permits the retort to be used with skelps of slightly different width. Oxygen for the secondary combustion is supplied from a conduit 82 in the center block. This conduit communicates with the torch chambers 71 through slots 83.

35 Air for secondary combustion is aspirated around the sides of the torches 78 and 79, but the upper sides of the torch chambers may be completely closed and all of the oxygen for the secondary combustion supplied under pressure through the slots 83 or similar passages in the side blocks or in a cover extending between the side blocks, or some of the oxygen for the secondary combustion may be supplied through such passages and some through the flame jet orifices of the torches.

40 The side blocks 63, 64, are cooled by liquid flowing through passages 84, 84'. The center block 67 is cooled by liquid flowing in a cooling chamber 85, best shown in Fig. 9.

45 The torches 78 and 79 are similar to the torches in the retort 30, with the exception of a slight curve at the ends of the torches 78 and 79 shown in Fig. 2. This curve of the torches enables them to follow the edges of the skelp as they move toward each other when approaching the final forming pass.

50 The skelp edges come together in the bite of rolls 86, 87 in the stand 25 to complete the forming operation and produce a welded pipe or tube. The weld is preferably rolled down immediately between the upper roll 86 of the final forming pass and a roller 88 (Fig. 9) inside of the tube. The roller 88 is supported by a roller 89 which bears against the bottom of the tube. These rollers 88 and 89 have their axes on the center line of the rolls 86 and 87, and are held against movement lengthwise of the tube by axles which extend from both sides of the rollers into slots in the bifurcated end of a mandrel 91.

55 An end piece 92 is fastened to the mandrel between the bifurcations. This end piece follows the curve of the roller 88 above the axle of the roller and limits the movement of the roller in the vertical slots of the mandrel so that the roller axles can not come out of the slots when the roller is not in a tube. The end piece 92 extends part way under the lower roller 89 and prevents it from dropping out of the mandrel slots when not supported by a tube.

60 The mandrel 91 is connected, by pins 94, at its forward end, to an extension of the center block 67. A conduit 95 through the mandrel 91 registers with a passage 96 which leads to the cooling chamber 85 of the center block 67. Water is discharged on the rollers 88 and 89 from the conduit 95 to cool the rollers.

65 The upper roller 88 is crowned and the radius of the crown is the inside radius of the pipe, as shown in Fig. 10. The lower roller 89 has a similar crown except for a center groove 97 which is provided to increase the area of bearing contact between the rollers 88 and 89.

70 Fig. 12 is a longitudinal sectional view of the torch 78 showing the chamber 88 from which the fuel and oxygen mixture is discharged through the jet openings 98. The torch is cooled by the circulation of water through conduits 100 (Figs. 8 and 12). The gas is supplied to the chamber 88 through a stem 102, which corresponds with 75 the stems 42 of the torches shown in Fig. 7.

75 Figs. 13 and 14 are transverse sectional views through the retort 31. This retort is supported by the base 48 and has blocks 104 which guide the skelp when the forward end of the skelp first enters the retort. A center block 105 is held over the skelp by transverse supports 106.

80 The retort 31 comprises retort bodies 108 and 109, which are illustrated diagrammatically in Figs. 13 and 14. These retort bodies are similar 75

in construction to the retort bodies 44 and 45 shown in Fig. 7, except that the retort bodies 108 and 109 and their torches 110 are warped to follow the edges of the skelp as the skelp bends 5 from its flat condition in the retort 30 to its substantially U-shaped contour in the bite of the rolls 32 and 33. Passages for cooling liquid and other details shown in the retort bodies in Fig. 7 are omitted in the diagrammatic illustration of Figs. 10 13 and 14.

The blocks 104 and center block 105 confine the products of combustion which issue from the retort bodies 108 and cause these products of combustion to flow over the surface of the skelp. 15 There are grooves 112 in the faces of the blocks 104 and center block 105. The blocks 104 are separated to provide a slot 113 between them and have passages 114 recessed in their opposing side faces and bottom faces for the escape 20 of products of combustion which flow across the bottom face of the skelp. The center block 105 has passages 115 and 116 for the escape of the products of combustion which flow across the top surfaces of the skelp.

25 The invention has been described as applied to the manufacture of pipe or tubing from a billet in a continuous operation, but it will be understood that certain features of the invention are applicable to the manufacture of pipe or tubing 30 from preheated skelp or even from cold skelp. The invention is not limited to the embodiment illustrated, and features of the invention may be used without others.

I claim:

35 1. The combination with a rolling mill which rolls metal to a flat skelp, of tube forming apparatus into which the skelp passes as it comes from the last stand of the rolling mill, a plurality of roll stands in said forming apparatus, and 40 means for raising the edge faces of the skelp to a welding state by the time they come together in the final forming stand while traveling at the speed of delivery of the skelp from the rolling mill, said means comprising retorts located along the 45 run of the skelp or partially formed tube between successive roll stands through which the metal passes, and devices in the retorts for projecting intense heating flames directly against the longitudinal edge faces to be welded.

50 2. Apparatus for making welded tubes from a heated billet in a continuous operation, said apparatus comprising a rolling mill in which the billet passes through successive roll stands and is worked into a flat skelp, a forming mill beyond 55 the last stand of the rolling mill in position to receive the skelp as it comes from the rolling mill, at least two forming passes through which the skelp travels successively in the forming mill, and heating retorts constructed and arranged to project flame jets directly against the edge faces of the skelp to bring the edges to a welding condition prior to their passage through the last forming pass, said retorts being located between several successive mill passes so that the 60 metal is subjected to the working of one or more roll stands during the heating of the edge faces.

65 3. A continuous process for making a welded tube from a heated billet, which process comprises rolling the billet to a flat skelp, forming the skelp as it comes from the last rolling step, raising the temperature of the edge faces of the skelp to surface fusion during the forming step by projecting flame jets directly against the edge 70 faces to be welded, and bringing said edge faces

together during the forming step while in a state of surface fusion.

4. A continuous process for making a welded tube from a heated billet, which process comprises rolling the billet to a flat skelp, forming the skelp in at least two forming passes immediately after the final rolling pass and while the metal is still at a high temperature, increasing the heat of the edge portions of the skelp by projecting gas jets directly against the edge 10 faces to be welded as they travel between the forming stands, and proportioning the heating effect of said jets and the speed of travel so that the jets raise the edges to a welding state just ahead of the final forming stand. 15

5. In a continuous process in which a billet passes progressively through a rolling mill and a tube forming mill, each of which includes a plurality of roll passes, the improvement of raising the temperature of the longitudinal edge 20 faces of the metal during their travel between some of the last roll passes by projecting flame jets directly against the edge faces, applying said flame jets to the run of metal between several roll stands so that the metal is subjected to the 25 working of one or more roll stands during the heating of the edge faces, and proportioning the heating of the flame jets to the speed of travel of the edge faces so that said edge faces are heated to a welding condition by the time they are 30 brought together in the final forming pass.

6. The method of manufacturing pipe and tubing from a heated billet which comprises rolling the billet to a flat skelp, progressively forming the skelp into a tube immediately after the final 35 rolling step and as a continuous operation with the final rolling step, and bringing the edge faces of the tube to a welding condition during the forming of the tube by projecting heating flames directly against the edge faces to be welded. 40

7. A method of making welded pipe and tubing from a skelp traveling at the speed at which such skelp is discharged from the final pass of a rolling mill, said method including operating on the metal at two regions spaced along the 45 length of the skelp to form the metal progressively into a tube, bringing the edge faces of the rapidly moving skelp to a welding condition during its travel between said regions by projecting high temperature flame jets directly against the 50 edge faces to be welded, and protecting the heated skelp from oxidation by causing the products of combustion of the flame jets to flow inward from the edge faces and blanket the surfaces of the partially formed tube. 55

8. A method of making welded pipe or tubing from flat, heated skelp traveling at high speed, including forming the skelp by bending forces applied in at least two regions spaced longitudinally along the skelp, and bringing the edge faces 60 together with the final bending force, and raising the edge faces of the rapidly moving skelp to a welding condition during the forming of the skelp by projecting intensely hot flame jets directly against the edge faces to be welded to heat 65 said edge faces substantially uniformly across their width between the regions where said bending forces are applied, and so proportioning the heating and the speed of travel that the edge faces are heated to a welding condition by the 70 time they reach the region where the final bending force is applied.

9. In the manufacture of pipe and tubing by passing a flat skelp through a forming mill in which successive roll passes operate simultane- 75

ously on different portions of the same skelp to progressively form said skelp into a tube and bring the seam edges together, the improvement of applying intense heating flames to the edge faces of the skelp while moving it through the forming mill at high speed, projecting said flames directly at the faces of the skelp edges

to be welded to heat said faces substantially uniformly across their width, and so proportioning the heating and the speed of travel that the edge faces are heated to a welding condition before they reach the final forming pass.

JAMES L. ANDERSON.
